UNITED STATES PATENT OFFICE.

WALTER E. BARNARD, OF HARTFORD, CONNECTICUT, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,274,365.

Specification of Letters Patent.

Patented Aug. 6, 1918.

Application filed July 2, 1912. Serial No. 707,153.

To all whom it may concern:

Be it known that I, WALTER E. BARNARD, a citizen of the United States, residing in Hartford, in the county of Hartford and 5 State of Connecticut, have invented certain new and useful Improvements in Combined Type-Writing and Computing Machines, of which the following is a specification.

This invention relates to computing machines, and particularly to those in which key-controlled power-driven mutilated gearing or the like is used to control the master wheel; either the master wheel or the dial 10 wheels being arranged to move step-by-step 15 at the operation of the keys.

The drawings show an improved means for connecting the keys of the typewriter to a set of power - driven mutilated gears, whereby the keys may selectively connect 20 the master wheel to any of said gears.

One of the features of the present invention is to improve the connection from the keys to the clutches which control the gears, and also to improve the construction and 25 operation of the clutches themselves.

Another feature of the invention resides in guarding against premature advance movement of the carriage before the master wheel completes its rotation. By means of a 30 detent associated with the clutch mechanism, the escapement wheel of the typewriter carriage may be automatically prevented from rotating prior to the completion of the rotation of the master wheel, thus holding the 35 carriage stationary during the computing operation.

Another feature resides in the provision of improved means for disconnecting the keys from the computing mechanism, 40 whereby positive disconnection is assured and liability of error through too rapid action of the computing mechanism is avoided.

Another feature is the provision of improved means for securing the action of the 45 computing mechanism by the initial portion of the printing stroke of the key of the typewriter, and permitting the key to complete its printing stroke independently of the computing mechanism.

50 Other features and advantages will hereinafter appear.

In the accompanying drawings,

Figure 1 is a side view in elevation.

Fig. 2 is a detail section, showing the relation of one of the clutches and its associated dog when the clutch is not connected to the shaft.

Fig. 3 is a vertical section through one of the clutches, taken at right angles to the view shown in Fig. 2.

Fig. 4 is a detail perspective view, showing the means for locking the escapement wheel until after the computing mechanism has finished its action.

Fig. 5 is a vertical section taken from 65 front to rear, to show the connection of the numeral keys to the linkages, whereby the numeral keys control the operation of the computing mechanism.

Fig. 6 is a front view in elevation, part 70 broken away, to show the underlying structure.

Fig. 7 is a diagrammatic view, showing a series of sections to illustrate the set of mutilated gears with the cams and gears driven 75 thereby.

Fig. 8 is a detail perspective view, showing the linkages from the numeral keys to the clutches on the drive shaft.

Fig. 9 is a slightly enlarged detail view 80 of certain parts shown in Figs. 2 and 6, showing one of the dogs moved forward to its releasing position, so that the clutch is connected in driving relation with the shaft, and so that the universal bar is just about to 85 release the actuated trip from its tripper.

Fig. 10 is a spread perspective view, showing the parts of one of the clutches separated one from another to disclose more 90 clearly their structure.

Fig. 11 is a vertical section through one of the clutches taken at right angles to the view shown in Fig. 8.

Fig. 12 is a fragmentary vertical section, showing in full lines the stem of one of the 95 numeral keys partly depressed to actuate its associated bell crank, and in dotted lines fully depressed, illustrating the fact that the actuation of the bell crank and the associated mechanism takes place solely during the initial part of the downstroke of the 100 numeral key.

Alphabet keys 1 and numeral keys 2 depress levers 3 to vibrate bell cranks 4, which swing type bars 5 up against a platen 6. The latter is mounted in a carriage 7 propelled 5 by the usual spring barrel, (not shown). The carriage has a rack 8 to mesh with a pinion 9, which is connected to an escapement wheel 10. Dogs 11, 12 control the movements of said escapement wheel. Each 10 type bar has a heel 13, so that it may press rearwardly a universal bar 14, which operates the dogs 11, 12, whereby letter feeding movements of the carriage are caused at the type strokes, as is usual in an Underwood 15 front-strike typewriting machine.

From the numeral keys 2 depend stems 15, guided at their lower ends in a fixed comb 16. Each of these key stems is designed to control the operation of a clutch-closing device 20 vice of the computing mechanism, there being one clutch for each numeral key. Separate trains of movement - transmitting mechanism extend from the stems 15 to the clutches. Considering one of these trains, a bell crank having an upright arm 17 and rearwardly extending arm 18, is loosely mounted below its associated stem 15. Arm 18 depresses an arm 19 fixed on the forward end of a horizontal rock shaft 20, so as to 30 swing an upright arm 21 also provided on the rock shaft. A transverse link 22 has a pin 23, engaged by said upright arm 21, to drive the link endwise. Said link is supported by idle links 24, 25, and has a stem 35 26. By means of a link 27, said stem 26 is connected to a clutch-controlling tripper arm 28, pivoted upon a fixed rod 29. There is an array of said tripper arms extending from front to rear, one arm for each numeral key. The tripper arm in each instance is adapted to operate a clutch controller, comprising a trip 30 and a latch or dog 31 pivotally connected to said latch at 45 57. Said dog is normally in engagement with a tooth or tongue 32 provided on the clutch, to restrain the clutch from closing. The arm 28 pulls the dog 31 away, to release 33 and permit the clutch to close. Each latch or dog 31 is slidably supported at one 50 end (see Fig. 9) in an opening 31^a in a supporting member secured to the machine frame, and at a point somewhat removed from its other end by the spring 58. Each dog is also supported, in part, by the spring- 55 pressed trip 30, which rests upon the upper end of the tripper-arm 28. Said dogs are maintained in their proper spaced relation by a comb plate 31^b. It is to be understood that there is one of these clutches and one of 60 these trains for each numeral key from "1" to "9". The clutches are loosely mounted on a power-driven shaft 33, which may be constantly revolving.

When a key stem 15 is depressed, the associated bell crank 17, 18, is rocked in clock-

wise direction at Fig. 5, and the arm 18 is caused to depress the arm 19 on the corresponding rock shaft 20. The arm 21 on said rock shaft is thus caused to pull the link 22 toward the left at Fig. 8, together with the 70 stem or riser 26 thereon, and through the associated link 27 to rock the tripper arm 28, whereby the trip 30, together with the dog 31, is drawn to the left at Fig. 7, to release the tongue 32 and thereby permit the 75 clutch to close, so that the clutch will be given a revolution by the power shaft 33.

With the clutches are associated mutilated gears 34, seen at Fig. 7, one gear to each clutch. These gears are designed to engage 80 pinions 35, which are all fixed upon a horizontal shaft 36, Fig. 1, which has a bevel pinion 37 to mesh with a bevel pinion 38 upon a vertical drive shaft 39, carrying at its top a pinion 40 to mesh with a pinion 41 fixed on a horizontal shaft 42, which carries a master wheel 43, to engage any of a series of computation wheels 44 in an adding head or totalizer 45, which has dial wheels 46. The adding head is connected by an arm 47 90 to the typewriter carriage 7, so that the computation wheels 44 are presented one at a time to the master wheel 43 to be rotated thereby.

The improvements are adapted to a variety of computing machines, to rotate many kinds of master wheels, which may be otherwise connected to be operated.

When any numeral key is depressed, its corresponding rotary clutch closes, and thereby connects the associated mutilated gear with the power shaft 33 so that said gear may engage the associated pinion 35, and rotate the pinion; shaft 36 thus turning the described connections to rotate the master wheel 43 to an extent dependent upon the key operated.

It will be seen at Fig. 7, that the first mutilated gear has only one tooth corresponding to numeral key "1" and is marked "1", the second gear has two teeth, corresponding to numeral key "2", and so on, the last gear in the series having nine teeth. Each of the pinions 35 has ten teeth; and the gears are adapted to turn the pinions either 110 one or more full tenths of a revolution, dependent upon the number of teeth in the gears; the last gear marked "9", being adapted to turn its pinion through nine-tenths of a revolution, whereby the master wheel 43 115 is turned sufficiently to cause the active dial wheel 46 to rotate nine points. Thus the depression of any numeral key operates to connect the power shaft 33 to the mutilated gear having the corresponding number of 120 teeth, whereby said power shaft 33 is caused to rotate the active dial wheel 46 to a corresponding extent.

Each of the clutches may comprise a normally stationary cup-like member 48 (fixed 130

to its associated mutilated gear 34) and a roller 49, which may be caused to jam between the said cup 48 and a hub or boss 50, provided upon the shaft 33, and rotating therewith. The ball or roller 49 runs in a hollow or pocket 51 in the inner side of the cup 48. This pocket is large enough at one end to permit the roller 49 to fit loosely without connecting the cup to the hub. The 5 pocket gradually grows shallow toward its opposite end so that the roller 49 can be jammed between the hub and the cup, forming a clutch connection. The roller or clutch member 49 is shifted by an annular member 52, which surrounds the hub 50 within cup 48, and has a notch 53 within which the ball 49 is confined. Spring 54 constantly tends to force the annular member 52 forward to move the ball 49 to clutch-closing position in the shallow portion of the pocket 51, so as to jam the ball or roller 49 between the hub 50 and the cup 48, to cause power to be transmitted from the shaft 20 to the cup 48 and the mutilated gear 34 25 fixed thereto.

The dog 31 normally holds the clutch open (Fig. 2) by restraining the tongue or projection 32 which extends from the annular member 52 through the cup 48 to a position 30 to be engaged by the dog 31. Since the rollers 49 lie normally in deep portions of the pockets 51, the shaft 33 and hubs 50 are allowed to rotate idly. When any dog 31 is withdrawn, by means of the associated numeral key 2, from the path of the tongue or projection 32, the spring 54 advances the annular member or ring 52 to shift the roller 49 along the pocket 51, to close the clutch, so that the shaft 33 may rotate the associated 35 mutilated gear 34, for the purpose already explained.

In the form of the invention illustrated in the drawings, the release of the tongue 32 and the consequent closing of the clutch, occurs near the beginning of the downstroke 45 of the numeral key; and since the shaft 33 may rotate at high speed, it oftentimes happens that said shaft completes a revolution even before the key completes its down- 50 stroke.

In order to avoid a second or spurious revolution of the mutilated gear, however, prior to the release of the key by the finger of the operator, a positively acting automatic 55 disconnection is effected between the key and the clutch opening dog 31, so that said dog may return to its normal position and arrest the tongue 32 and open the clutch before it is possible for the mutilated gear to 60 make the second revolution. To this end, a universal power-driven releasing bar 100 is provided for the trips 30. To operate this bar, each of the mutilated gears 34 is provided with a disk 67 having a cam 68 in position to engage one of a set of arms 69, all fixed

to a rock shaft 70; so that, when any cam rotates, the shaft 70 is rocked. On this rock shaft a bar 100 is supported by arms 101, so as to be swung upwardly when the shaft rocks, that is, when any of the clutches is 70 closed and rotates the associated cam 68. The bar 100 underlies points which the forward ends of the trips 30 will occupy when advanced to release the tongue 32 from the latch or dog 31, so that, when the bar 100 is 75 moved upwardly, any trip or pawl 30 which happens to be advanced will be lifted, against the tension of its spring 59, clear of the associated tripper 28; whereby an associated spring 58 will be free to draw 80 the latch or dog 31 back to normal position in the path of the rotating tooth 32. This return movement of the dog 31 may even occur before the initial stroke of the tripper arm 28 is completed. The opening of the 85 clutch occurs, therefore, automatically and wholly independently of the release of the finger key by the operator.

It will be understood, however, that upon release of the key, the nose of the pivoted 90 trip 30 will be again snapped over the top of the tripper arm 28 by means of the spring 59. It will be understood that when the dog 31 intercepts tooth 32, the ring 52 is arrested, and the roller 49 is forced back 95 into the cup 48, thus relieving the jam of hub 50 and cup 48, and allowing the power shaft 33 again to rotate idly.

The disconnection of 31 from 32 permits the clutch device and its gear to rotate rapidly independently of the speed of operation of the key; while the disconnection of 30 from 28 insures that the dog 31 shall return in time enough to intercept the rapidly rotating tongue of the clutch so that the latter 100 is also permitted to rotate at very high speed, regardless of the speed of operation of the finger key.

It will be seen at Fig. 5 that the key stem 15 stands normally close to the arm 17, so that almost at the beginning of the downstroke of the key, said stem 15 will engage the arm 17 and rock the latter enough to effect the withdrawal of the dog 31 from the clutch, tongue or tooth 32, so that the clutch 110 is promptly released. The bottom of the stem 15 is beveled at 60 to engage a cam edge 61 offset to one side on the arm 17, for the purpose of camming said arm to the right at Fig. 5 during the early part of the key-stroke; the position and shape of the parts permitting the keys 2 to complete their printing strokes while the arm 17 remains stationary, the rear edge of the key stem 15 riding idly down past said arm. That is to say the computing action is started at the initial part of the down stroke of the numeral key and the connecting train remains unactuated thereby during the rest of the 115 stroke of the key.

To prevent overthrow of the pinion shaft 36, there is fixed thereon a notched wheel 62, Fig. 6, in which is pressed a roll 63 provided on a lever 64, which is pivoted at 65 and operated by a compression spring 66.

To provide for temporarily locking the typewriter carriage 7 against traveling, while the master wheel 43 is rotating, advantage is taken of the rocking of the shaft 10 70 by the cams 68 and the arms 69 when any one of the mutilated gears is clutched to the drive shaft. One of arms 69 has an extension 71, which rocks, when the shaft 70 rocks and is connected to pull a link 72, thereby vibrating a lever 73, which is connected by a thrust link 74 to a dog or detent 75, and moves the latter from the normal ineffective position at Fig. 6 into engagement with the adjacent tooth of the escapement wheel 10 of the typewriter carriage 7, Figs. 4 and 6. As soon as the cam 68 passes the arm 69, the latter, together with the shaft 70, extension 71 and dog 75, are returned to normal positions by a spring 76. The parts may be so proportioned and constructed that this release of the escapement wheel by the dog 75 may generally occur before said escapement wheel is released by the dogs 11, 12; but the provision of the dog 75 will not only hold the carriage while the master wheel is being given a maximum rotation, but will also insure against the stripping of the teeth from the computing gears, in case of irregular action of the carriage feeding or other mechanism.

The cams 68 are shown to be of graded sizes corresponding to the number of teeth in the associated mutilated gears; so as to assure the inaction of the carriage during the period the teeth of the mutilated gears are active. The period will be shortest for the "1" key and cam, and longest for the "9" key and cam.

If it is desired to employ a full stroke mechanism for the numeral keys 2, there may be used a rack 77 attached to the key stem 15, and a pawl 78 pivoted to a mount 79, and having a draw spring 80, whereby it can coöperate with the rack 77 to prevent the same from moving in either direction before it has finished its stroke in one direction.

If desired, locks may also be added for preventing two keys from being operated simultaneously. These locks may be in the form shown in Fig. 6 at 81, and form an array across the machine, being individually pivoted at 82 to a part of the framework. Many of the locks are shown at Fig. 6 in contact, but any of the extensions 83 on the rack 77 may enter between any pair of locks, and force them apart, thereby closing the spaces of the locks in the remaining pairs, so that no other key can descend before the depressed key rises.

Variations may be resorted to within the scope of the invention, and portions of the improvements may be used without others.

Having thus described my invention, I claim:

1. The combination with a computing head, of a carriage, a set of numeral keys, a set of power-driven gears for actuating said computing head variable amounts and each having a number of teeth corresponding to the value of the associated numeral key, means for releasing the gears from the control of the keys, and means controlled from said mutilated gears for preventing the movement of said carriage until after said gears have performed their work.

2. The combination with a computing head, of a carriage, a set of numeral keys, a set of power-driven gears for actuating said computing head variable amounts and each having a number of teeth corresponding to the value of the associated numeral key, means for releasing the gears from the control of the keys, an escapement mechanism for said carriage, and means controlled from said gears for interfering with the complete action of said escapement mechanism until any one of said gears in action has completed its work.

3. The combination with a computing head, of a carriage, a set of numeral keys, a set of gears for actuating said computing head variable amounts, each having a number of teeth corresponding to the value of the associated numeral key, a set of cams, one connected to each of said gears, said cams being of graded magnitudes and corresponding in magnitude to the number of teeth on the associated gear and means operable by any one of said cams for preventing the movement of said carriage until the teeth of the associated gear in action have done their work.

4. The combination with a computing head, of a carriage, a set of numeral keys, a set of gears actuated by said numeral keys and adapted to actuate said computing head variable amounts, each of said gears having a number of teeth corresponding to the value of the associated numeral key, a cam connected to each of said gears, said cams being of graded magnitudes and corresponding magnitude to the number of teeth on the associated gear, arms actuated by said cams, one of said arms having a link connected thereto, an escapement mechanism for said carriage, and a detent operatively connected to said link so as to engage a portion of said escapement mechanism to prevent its operation until the action of the active cam has ceased.

5. In a computing machine, in combination, a traveling carriage, means including a set of number keys for effecting step-by-step movements thereof, a set of computing

wheels, a master actuator therefor, connecting means for effecting denomination-selecting changes of relative position between said actuator and said wheels in accordance with 5 said step-by-step movements of said carriage, operating mechanism for said actuator including valuating means and motive means therefor, means individual to each key and effective on depression thereof to initiate a 10 selective operation of said valuating means by said motive means to effect a movement of said actuator corresponding in extent to the number represented by the key depressed, means for automatically disconnecting said key-controlled-operation-initiating means on initiating such operation, and for rendering said means incapable of further affecting the movements of the parts of said mechanism thus called into action until said 15 key has been returned to its normal position, means for arresting the moving parts of said mechanism after a predetermined cycle of movements, and means controlled by said operated valuating means for preventing a 20 denomination-selecting movement of said carriage during the operation of said actuator by said valuating means.

6. The combination with a computing head, of a master wheel, said computing head and said master wheel having a relative step-by-step movement, a set of numeral keys, a set of power-driven mutilated gears controlled in their action by said numeral keys to drive said master wheel variable 30 amounts, and each having a number of teeth corresponding to the value of the associated numeral key, means to automatically release each mutilated gear from its key, and means controlled from said mutilated gears 35 for preventing the relative movement of said computing head and said master wheel while said mutilated gears are in action.

7. The combination with a computing head, of a set of numeral keys, a set of 45 mutilated gears for driving said computing head variable amounts, each of said mutilated gears having a number of teeth corresponding to the associated numeral key, a continuously driven shaft, a clutch for 50 connecting each of said gears to said shaft, said clutches normally tending to connect said gears in driving relation with said shaft, a disconnector for preventing the connection of said clutches in driving relation 55 with said shaft, linkages connecting the individual disconnectors with corresponding numeral keys, whereby said numeral keys can actuate said disconnectors to release said clutches, and clutch actuated means for 60 disconnecting any actuated disconnector from its associated linkage, after the associated clutch has been connected to said shaft.

8. The combination with a computing head, of a set of numeral keys, a set of muti- 65

lated gears for driving said computing head variable amounts, each of said mutilated gears having a number of teeth corresponding to the associated numeral key, a continuously driven shaft, a clutch for connecting each of said gears to said shaft, said clutches normally tending to connect said gears in driving relation with said shaft, a disconnector for preventing the connection of said clutches in driving relation with said shaft, linkages connecting the individual disconnectors with corresponding numeral keys, whereby said numeral keys can actuate said disconnectors to release said clutches, a cam connected to each of said gears, an arm 70 operated by each of said cams, a rock shaft on which each of said arms is fixedly secured, and a universal bar connected to said rock shaft so as to be swung when any of said gears is connected to said shaft, said 75 universal bar underlying the forward position of all of said disconnectors, and being adapted to interrupt the connection between any of said disconnectors and its associated linkage, after the associated gear has been 80 clutched to said shaft.

9. The combination with a computing head, of a set of numeral keys, a set of gears controlled in their action by said numeral keys and connected to drive said computing 95 head variable amounts, each of said gears having a number of teeth corresponding to the value of the associated numeral key, a continuously driven shaft, a clutch for connecting each of said gears in driven relation with said shaft, a disconnector for each of said clutches for maintaining them in their unclutched condition, and linkages extending from said disconnectors to said keys, whereby said keys may control the clutching of said gears to said shaft, each of said 100 disconnectors comprising a locking dog and a trip pivotally connected so that said disconnectors can be operatively disconnected from said keys.

10. The combination with a computing head, of a mutilated gear for driving said computing head, a clutch for controlling the action of said mutilated gear, a disconnector for holding said clutch normally in its disconnected condition, a numeral key, a linkage from said numeral key to said disconnector, whereby said numeral key can actuate said disconnector to release said clutch, means for releasing said disconnector from 115 said linkage, and means for returning said disconnector to its disconnecting position.

11. The combination with a computing head, of a valuating mechanism for determining the extent of actuation of said computing head, a set of numeral keys, a stem connected to each of said numeral keys having a cam edge at its lower end, a set of bell cranks, each having a cam edge offset from the body of one arm thereof, so that said 125

keys can actuate said bell cranks for a fractional part of the downstroke, and idly passing said bell cranks during the remainder of their downward stroke, and linkages connecting said bell cranks to said valuating mechanism, whereby said keys can control the extent of actuation of said computing head.

12. The combination with a numeral key, 10 a stem connected to said numeral key having a cam edge at its lower end, a bell crank having a cam edge on one arm thereof offset from the body of said arm, an arm engageable by the other arm of said bell crank, a 15 rock shaft operated by said last-mentioned arm, a floating link, an arm connecting said rock shaft to said link, a tripper arm connected to said link, a disconnector operable by said tripper arm, said disconnector comprising a dog and a trip pivotally connected together, a gear, a constantly driven shaft for said gear, and a clutch connecting said gear in driven relation with said shaft, said clutch having a member normally engaged 25 by said dog to prevent the connection of said gear and said last-mentioned shaft by said clutch.

13. In a computing machine, in combination, a traveling carriage, means including 30 a set of number keys for effecting step-by-step movements thereof, a set of computing wheels, a master actuator therefor, connecting means for effecting denomination-selecting changes of relative position between said 35 actuator and said wheels in accordance with said step-by-step movements of said carriage, operating mechanism for said actuator including a set of graded valuating members, one for each key, and motive 40 means therefor, means individual to each key and effective on depression thereof to initiate a driving connection from said motive means through a corresponding valuating member to said actuator to effect a 45 movement thereof corresponding in extent to the number represented by the key depressed, means for automatically disconnecting said key-controlled-connection-initiating means on initiating such a connection, and 50 for rendering said means incapable of further affecting the movements of the parts of said mechanism thus called into action until said key has been returned to its normal position, means for arresting the moving 55 parts of said mechanism after a predetermined cycle of movements, and means controlled by the parts of said operating mechanism set in action by any of said keys for preventing a denomination-selecting 60 movement of said carriage during the operation of said actuator thereby.

14. In a computing machine, in combination, a traveling carriage, means including a set of number keys for effecting step-by-step 65 movements thereof, a set of computing

wheels, a master actuator therefor, connecting means for effecting denomination-selecting changes of relative position between said actuator and said wheels in accordance with said step-by-step movements of said carriage, operating mechanism for said actuator including a set of graded valuating members, one for each key, and motive means therefor, means individual to each key and effective on depression thereof to initiate 75 a driving connection from said motive means through a corresponding valuating member to said actuator to effect a movement thereof corresponding in extent to the number represented by the key depressed, means for automatically disconnecting said key-controlled-connection-initiating means on initiating such a connection, and for rendering said means incapable of further affecting the movements of the parts of said mechanism 80 thus called into action until said key has been returned to its normal position, means for restoring said key-controlled-connection-initiating means on the return of said key to its normal position, means for arresting the moving parts of said mechanism after a predetermined cycle of movements, and means controlled by the parts of said operating mechanism set in action by any of said keys for preventing a denomination-selecting 85 movement of said carriage during the operation of said actuator thereby.

15. The combination of a source of power, a master wheel or member, a stepped or asorted set of gears, a set of keys, means selectively operated by the keys for operatively connecting said source of power to said master wheel through any selected one of said gears, means operable by said source 100 of power for disconnecting the keys from said connecting means and for subsequently restoring the connection of the keys, and means for automatically disconnecting said master wheel from said source of power. 105

16. The combination of a stepped or asorted set of gears, a master wheel or member, a set of keys, means selectively operated by the keys for operatively connecting said master wheel to any of said gears, a source of power operating through said gears to drive said master wheel, means operable by said source of power effective upon the down strokes of the keys for disconnecting the latter from said connecting means, 110 and means to restore the key connection upon the return of the key to normal position.

17. The combination of a stepped or asorted set of gears, a master wheel or member, a set of keys, means selectively operated by the keys for operatively connecting said master wheel to any of said gears, a source of power operating through said gears to drive said master wheel, means operable by said source of power effective upon the down 115 strokes of the keys for disconnecting the latter from said connecting means, and means to restore the key connection upon the return of the key to normal position.

- strokes of the keys for disconnecting the latter from said connecting means, and means to restore the key connection upon the return of the key to normal position, 5 the disconnection of the key from the computing mechanism being independent of the speed of movement of the key.
18. The combination of a master wheel or member, a set of gears connected thereto, a set of mutilated gears for operating the first set of gears, a power shaft, a set of clutches to connect said mutilated gears to said power shaft, devices to control the closing of said clutches, keys, power-released connections between said keys and said closing devices, operative immediately upon the closing of any clutch to effect such release, means for automatically opening the clutches, and means to restore the connections 10 between the keys and said closing devices.
19. The combination of a master wheel, a power shaft, a set of mutilated gears, a set of normally open independent clutches arranged loosely upon said power shaft, keys, separate trains of connections extending from said clutches to said keys to enable any key to control the closing of its clutch, means for opening the clutches independently of the 15 keys, and means driven by the power shaft and called into operation upon the closing of any clutch, for disconnecting the train of connection from the closed clutch to the associated key.
20. The combination of a master wheel, a power shaft, a set of mutilated gears, a set of normally open independent clutches arranged loosely upon said power shaft, means normally tending to close the clutches, keys, 20 separate trains of connections extending from said clutches to said keys to enable any key to control the closing of its clutch, a dog for restraining each clutch, said dog movable by the connected key to release said restraining means, and means operable through said power shaft for disconnecting each dog from its key.
21. The combination of a master wheel, a power shaft, a set of mutilated gears, a set 25 of normally independent clutches arranged loosely upon said power shaft, means normally tending to close the clutches, keys, separate trains of connections extending from said clutches to said keys to enable any key to control the closing of its clutch, a dog for restraining each clutch, said dog movable by the connected key to release said restraining means, means operable through the power shaft for disconnecting 30 the dog from the key at the initial portion of the gear movement effected by the power shaft, and means to return the dog.
22. The combination of a master wheel, a source of power, a set of mutilated gears, a set of normally open independent clutches 35 to coöperate with said power shaft and said gears, means normally tending to cause each clutch to close, separate trains of connections extending from said clutches to said keys to enable any key to close its clutch, each train including a dog for restraining each clutch, said dog movable by the connected key to release said restraining means, means for opening the clutches independently of the return of the keys, a carriage for effecting 40 relative denominational movement between the master wheel and the computing wheels, and means graded according to the mutilation of the gears, for preventing movement of the carriage while the master wheel is rotating.
23. The combination with a typewriter including a carriage and means including a set of type-operating number keys for effecting letter-spacing movements thereof, of 45 a computing mechanism including a set of computing wheels, a master actuator therefor, connecting means for effecting denomination-selecting changes of relative position between said actuator and said wheels in accordance with the letter-spacing movements of said carriage, operating mechanism for said actuator including valuating means and motive means therefor, means individual to each key and effective on depression thereof 50 to initiate a selective operation of said valuating means by said motive means to effect a movement of said actuator corresponding in extent to the number represented by the key depressed, means for automatically disconnecting said key-controlled-operation-initiating means on initiating such an operation, the relation of said key-controlled means to the other parts of the computing mechanism, after a disconnection, being such 55 that said key may continue its downward movement, to cause the type operated thereby to print, and to return to normal position independently of any predetermined time-relation, and free from possible interference with the movements of the parts of said mechanism set in operation thereby, means for arresting the moving parts of said mechanism after a predetermined cycle of movements, and means controlled by said 60 operated valuating means for preventing a letter-spacing movement of said carriage during the operation of said actuator by said valuating means.
24. The combination with a series of numeral keys, of valuating mechanism for determining the extent of computation according to the value of the numeral key actuated, make - and - break connections between said valuating mechanism and said numeral keys 65 whereby the former may be controlled from the latter, and means for controlling the continuity of said connections from said valuating mechanism.
25. The combination with a series of nu- 70

meral keys, of valuating mechanism for determining the extent of a computation according to the value of the numeral key actuated, make-and-break connections between 5 said numeral keys and said valuating mechanism whereby the latter may be controlled from the former, and breaking means operated from said valuating mechanism for interrupting said connections after said valuating mechanism comes into play, so that 10 said keys may be caused to complete their movements during, and independently of, the further operation of said valuating mechanism.

15 26. The combination with a series of numeral keys, of valuating mechanism for determining the extent of a computation to correspond with the value of a numeral key actuated, and make-and-break connections 20 between said numeral keys and said valuating mechanism whereby said numeral keys, which are normally in dominance over said valuating mechanism, may start said valuating mechanism in action and lose dominance 25 thereover, said connections including a trip, a tripper arm for actuating said trip, a linkage for operating said tripper arm, and a disconnector for positively breaking the connection between said trip and said tripper arm.

30 27. The combination with a series of numeral keys, of valuating mechanism for determining the extent of a computation to correspond with the value of a numeral key actuated, and make-and-break connections 35 between said numeral keys and said valuating mechanism whereby said numeral keys, which are normally in dominance over said valuating mechanism, may start said valuating mechanism in action and lose dominance 40 thereover, said connections including a dog for said valuating mechanism, a trip for said dog, a tripper arm for actuating said trip, a linkage for operating said tripper arm, and a disconnector for engaging said trip to move it out of engagement with 45 said tripper arm.

50 28. The combination with a series of numeral keys, of valuating mechanism for determining the extent of a computation to correspond with the value of a numeral key actuated, and make-and-break connections 55 between said numeral keys and said valuating mechanism whereby said numeral keys, which are normally in dominance over said valuating mechanism, may start said valuating mechanism in action and lose dominance 60 thereover, said connections including a dog for said valuating mechanism, a trip for said dog, a tripper arm for actuating said trip, a linkage for operating said tripper arm, a disconnector for engaging said trip to move it out of engagement with said tripper arm, and means for operating said

65 disconnector from said valuating mechanism when the latter comes into play.

29. The combination with a series of numeral keys, of a series of valuating devices, one for each of said numeral keys and having a driving capacity corresponding to the 70 accordant numeral key, and a series of connections, one individual to each numeral key and each valuating device for enabling a corresponding numeral key to bring its accordant valuating device into action, said 75 connections including a series of trips, a series of tripper arms for actuating said trips, and a bail universal to all of said trips for disengaging any of said trips from said tripper arms when in its actuated position. 80

30. The combination with a series of numeral keys, of a series of valuating devices, one for each of said numeral keys and having a driving capacity corresponding to the 85 accordant numeral key, and a series of connections, one individual to each numeral key and each valuating device for enabling a corresponding numeral key to bring its accordant valuating device into action, said 90 connections including a series of trips, a series of tripper arms for actuating said trips, a bail universal to all of said trips for disengaging any of said trips from said tripper arms when in its actuated position, and 95 means for operating said bail from any one of said valuating devices.

31. The combination with a typewriter including a carriage and means including a set of type-operating number keys for effecting letter-spacing movements thereof, of a computing mechanism including a set of computing wheels, a master actuator therefor, connecting means for effecting denomination-selecting changes of relative position 100 between said actuator and said wheels in accordance with the letter-spacing movements of said carriage, operating mechanism for said actuator including a set of graded valuating members, one for each key, and motive means therefor, means individual to each key and effective on depression thereof to 105 initiate a driving connection from said motive means through a corresponding valuating member to said actuator to effect a movement thereof corresponding in extent to the number represented by said key, means for automatically disconnecting said key-controlled-connection-initiating means on initiating such a connection, the relation of said key-controlled means to other parts of the computing mechanism, after disconnection, being such that said key may continue its downward movement, to cause the type controlled thereby to print, and to return to normal position independently of any pre-determined time-relation, and free from possible interference with the movements of the parts of said mechanism set in operation 110 115 120 125

thereby, means for arresting the moving parts of said mechanism after a predetermined cycle of movements, and means controlled by the parts of said operating mechanism set in action by any of said keys for preventing a letter-spacing movement of said carriage during the operation of said actuator thereby.

32. The combination with a series of numeral keys, of a series of power-driven valuating devices one individual to each of said numeral keys and having a driving capacity corresponding to the value of its accordant numeral key, a series of computing wheels, actuating mechanism for said computing wheels, traversing mechanism for effecting a relative movement between said actuating mechanism and said computing wheels, connections enabling any one of said valuating devices in action to drive said actuating mechanism, and automatic means brought into play by any of said valuating devices to prevent an action of said traversing mechanism while any of said valuating devices is in operation, whereby the active computing wheel is locked against traveling movement only while it is being driven by the selected valuating device.

33. The combination with a series of computing wheels, of actuating mechanism for said computing wheels, a carriage for effecting a denominational selection between said computing wheels and said actuating mechanisms, a series of numeral keys, a series of valuating devices one for each of said numeral keys and having a driving capacity corresponding to the accordant numeral keys, a single connection from all of said valuating devices to said actuating mechanism whereby the motion of any one of said valuating devices will be transferred to said actuating mechanism and hence to one of said computing wheels, locking mechanism for preventing a movement of said carriage, and shifting means operating from any and all of said valuating devices for bringing said locking mechanism into play when any one of said valuating devices is in action so as to prevent a movement of said carriage and thus a relative traveling movement between said computing wheels and said actuating mechanism.

34. The combination with a series of numeral keys, of computing mechanism, valuating mechanism for driving said computing mechanism amounts corresponding to the numeral keys actuated, denominational selecting mechanism for recording the amounts in the proper denominational columns in the computing mechanism, connections from said numeral keys to said valuating mechanism rendering said valuating mechanism normally subservient to said numeral keys, locking mechanism for preventing denominational selecting movements, tripping mechanism for breaking the continuity of the connections between said numeral keys and said valuating mechanism so that a numeral key, after starting said valuating mechanism in action, will no longer be in dominance thereover, and cam means operated from said valuating mechanism and having the dual capacity of actuating said locking mechanism and said tripping mechanism.

35. The combination with a typewriter carriage, of a computing mechanism having a series of valuating members of graded driving capacities, a series of numeral keys for controlling the action of said carriage, and the action of said computing mechanism with said valuating members, locking means for said carriage, and graded controls associated with said valuating members to operate said locking means and maintain the same in action for varying periods corresponding to the driving capacities of the associated valuating members.

36. In a computing machine, the combination with numeral keys and computing wheels, of a power shaft, clutches under the control of said keys for causing said wheels to be turned by said shaft, each clutch forming part of an indexing device for turning said wheels, a traveling carriage for selecting the wheel to be turned, an escapement for said carriage controlled by said keys independently of said shaft, a lock for holding said carriage, and a connection whereby any clutch while turning makes said lock effective.
